(57) **CLAIM**

The ornamental design for a sweep for a door, swinging panel, and the like, as shown and described.

DESCRIPTION

FIG. 1 is an isometric view of a sweep for a door, swinging panel, and the like.

FIG. 2 is a first end elevation view thereof.

FIG. 3 is a second end elevation view thereof.

FIG. 4 is a first side elevation view thereof.

FIG. 5 is a second side elevation view thereof.

FIG. 6 is a top plan view thereof; and,

FIG. 7 is a bottom plan view thereof.

In FIGS. 1 and 4–7, the sweep for a door, swinging panel, and the like is shown with a symbolic break along its length. The appearance of any portion along its length between the break lines forms no part of the claimed design. Furthermore, in FIGS. 1 and 4–7, portions at the first end and second end thereof are shown in broken lines, and these portions form no part of the claimed design.
